UNITED STATES PATENT OFFICE.

WLADIMIR LORENC AND VICTOR LORENC, OF BUDAPEST, AUSTRIA-HUNGARY.

POWER-TRANSMITTER.

No. 810,780.

Specification of Letters Patent.

Patented Jan. 23, 1906.

Application filed December 24, 1901. Renewed May 27, 1905. Serial No. 262,683.

To all whom it may concern:

Be it known that we, WLADIMIR LORENC and VICTOR LORENC, engineers, residing at Budapest, Austria-Hungary, have invented 5 new and useful Improvements in Power-Transmitters, of which the following is a specification.

Our invention relates to an improved power-transmission mechanism.

10 The object of our invention is to provide a power-transmission device by which a driving member making periodical movements in constant intervals of time and capable of giving a constant amount of energy at each periodic movement can be used to overcome a varying resistance.

Our invention differs radically from the power-transmitting devices heretofore known, as will be clear from the following explanation: In the old forms of power-transmitting devices the prime mover or driving member has at all times a connection to the driven member of such kind that there is at all times a constant load on the said prime mover, 20 which is assumed to move at a constant speed under such constant load. By the old forms of variable-power-transmission devices merely the ratio of power transmission is changed in such a way that the speed of the driven member multiplied by the force given to it is, neglecting friction, at all times equal to the speed of the driving member multiplied by the force which said driving member possesses. In our invention, however, while the driving member makes each periodical movement in 25 the same interval of time and the total work done at each periodical movement is constant still the rate of doing such work is not necessarily constant during the different portions 30 of a single period. As is well known, any prime mover or driving member when in operation has a certain kinetic energy represented by the equation $K = \frac{1}{2} MV^2$, in which K equals kinetic energy, M equals mass of the 35 moving parts, and V equals velocity of the moving parts. The force necessary to absorb this kinetic energy—that is to say, the force necessary to stop the prime mover or driving member—will vary inversely with the 40 time during which it resists the prime mover or driving member. For example, if a force of ten pounds applied for one second will stop a prime mover then to stop it in one-tenth of a

second will require ten times the force or one hundred pounds, or, in other words, if the 55 prime mover will just overcome a resistance of ten pounds applied for one second it will overcome a resistance of one hundred pounds applied for one-tenth of a second.

In our power-transmission device the resistance is applied to the driving member during a portion only of the periodical movement of such driving member, the duration of the application being an inverse function of the resistance. During the remaining portion of 65 the periodic movement of the driving member it has an opportunity to store up its energy to be used during the succeeding periodical movement.

Our invention consists in the features, details of construction, and combination of parts, which will first be described in connection with the accompanying drawings and then particularly pointed out in the claims.

In the drawings, Figure 1 is a diagrammatic perspective view of one embodiment of our invention; Figs. 2, 3, 4, and 5, similar views illustrating modifications of our invention; Fig. 6, a detail perspective of another modification of our invention; Fig. 7, a similar view of still a further embodiment of the invention; Fig. 8, a side elevation, partly in section, illustrating the manner of applying one form of our invention; Fig. 9, a sectional view of another embodiment of our invention; Fig. 10, a similar view of still another modification, and Fig. 11 an end view of the same.

Referring to Fig. 1 of the drawings, which illustrates a simple embodiment of the invention particularly suitable for concrete illustration of the fundamental principles of our invention, A is a shaft, more particularly described hereinafter, journaled in bearings indicated in section at a. The shaft is provided 90 at each end with a crank-arm, as shown at B and C, respectively. In the present example the crank-arm C is shown as provided with a pawl D, arranged to coact with the ratchet-teeth e, formed on the interior face of a wheel E, to which wheel it is assumed the load or resistance to be overcome is applied in any suitable manner—as, for example, by placing a belt over the outer face of the wheel E and around a pulley on the machine to be driven, 95 which belt and the pulley which it drives are

not shown. The crank-arm B is intended to be oscillated through a constant arc and with a constant force by any suitable motor, (not shown,) the arm B being provided with a 5 wrist-pin *b*, to which the motor is connected. The arm B in moving through its arc makes a periodical movement—that is to say, considering one end of its arc as the initial point of movement, it moves from this initial point 10 and back to it again.

The shaft A is not rigid, but is a resilient member capable of a certain specific amount of distortion when subjected to a torsional strain and of returning to its initial condition 15 when the strain is removed. It is obvious that when the said shaft is subjected to a torsional strain it will give a reactive pressure against said strain equal to said strain. Moreover, the shaft is so arranged or proportioned 20 that it will give a maximum reactive pressure equal to the maximum strain to which it is to be subjected, with a distortion or angle of torsion substantially equal to and never less than the angular movement of the 25 crank-arm B. If now while the crank-arm B is oscillating the crank-arm C encounters no resistance, it is obvious that, if friction be neglected, there would be no distortion of the resilient member or shaft A, and the crank-arm C would move synchronously with the 30 crank-arm B. During the forward movement of the crank-arm C its pawl D would engage the ratchet-teeth *e*, and thereby rotate the wheel E, the angular movement of 35 the wheel E being equal to the angular movement of the arms C and B. If, however, the crank-arm C be opposed by a resistance sufficient to hold it stationary, the crank-arm B will still make its periodical movements, 40 but will exert its energy during its forward movement in twisting the shaft A, thus converting substantially all the kinetic energy of the driving member into potential energy, which, however, is restored to the driving member on the return stroke of the latter. 45 Thus the kinetic energy is not lost, but when converted into potential energy is afterward reconverted into kinetic energy and used in useful work on the driving member. If the 50 resistance to the movement of the crank-arm C be less than sufficient to hold it stationary, the movement of the crank-arm B will have the effect of first distorting or twisting the shaft A until the reactive terminal pressure 55 of the shaft is sufficient to overcome the resistance encountered by the arm C, whereupon the said arm C is moved forward through an arc equal to the difference between the normal angular movement of the 60 crank-arm B and the angular extent to which said arm B moved in distorting the shaft A to produce the desired reactive pressure. In other words, a part of the kinetic energy of the driving member B is converted into potential energy stored in the shaft A, while the 65

remainder of the kinetic energy of the driving member is transmitted as kinetic energy through the shaft A to the crank-arm C and is usefully employed in overcoming resistance.

The potential energy stored in the shaft A is returned to the driving member B as kinetic energy so soon as this starts on its return stroke. It is obvious, therefore, that the greater the resistance encountered by the 70 crank-arm C the shorter the arc through which it is moved, or, in other words, the shorter the arc through which the driving member or crank-arm B moves while subjected to such resistance. If the resistance 75 is almost zero, the driving member is subjected to it during almost the whole time of the forward stroke of said driving member. If the resistance is almost the maximum which the driving member can overcome, the 80 latter is subjected to said resistance only at the last portion of its forward stroke.

The resistance which the driving member encounters in twisting the shaft A is counterbalanced by the impetus which the driving 85 member receives from the torsional reaction of said shaft on the return stroke of said driving member. Therefore, neglecting friction, the work which the driving member has to do at each stroke is measured by the resistance 90 and the time during which the resistance is applied to said driving member. As the time of application of said resistance is an inverse function of the resistance, the driving member, while having a substantially constant energy, 95 may give out this constant energy in a variable manner—that is to say, may give a large force through a small interval of space or a small force through a large interval of space. Furthermore, the variation in the conversion 100 of power from the driving member is automatically determined by the resistance itself. It will be clear, therefore, that a construction 105 embodying our invention comprises a driving member, a driven member, and a resilient 110 member connected to the driving and driven members and capable of converting all the kinetic energy of the driving member into potential energy.

We are aware that it has been common 115 heretofore to connect driving and driven members by springs or resilient members generally for the purpose of preventing the transmission of shock from one part to the other for the purpose of overcoming dead-centers and for the purpose of compensating 120 or equalizing the unequal movements of two parts; but none, so far as we are aware, have produced a true power-transmission device by employing a resilient member having the 125 specific properties of ours.

The above-described action can also be effected by interposing at any point whatever between the pin *b* and the periphery of the wheel any suitable spring or a combina- 130

tion of such springs; but this spring or springs must, however, be of such a nature that it or they shall be capable of bearing a torsion or other elastic distortion corresponding with the full extent of oscillation of the arm B, so that the power impulses which are produced during this repeated maximum distortion shall be equal on the average to the maximum road resistance which is to be overcome. It is particularly advantageous to employ torsion-springs, because the weight thereof is smaller than that of flexible springs with equal power capacity. The straight torsion-spring when arranged in the manner indicated in Fig. 1 has the smallest moment of inertia. This circumstance is particularly important with a high speed of revolution of the motor, because the weight of springs designed for large powers and for the necessarily great distortion is considerable. In Fig. 2 instead of one straight torsion-spring rod three such rods A' are arranged parallel. An arrangement of this kind allows the transmission of greater driving moments with the same length of spring. Fig. 3 shows instead of a straight torsion-spring a cylindrical flexible spring A². In addition to this spring there are also rubber buffers F, which act as auxiliary springs and are not situated in the oscillating part, but allow an elastic angular displacement of the ratchet-wheel E' with relation to the wheel G, which it drives through the yoke G'. Thus in this case the auxiliary springs F, which are situated in the rotating part, are connected in series with the spring A², situated in the oscillating part. Furthermore, a compression-spring can be used in the oscillating portion of the mechanism—as shown, for example, in Fig. 4, where two compression-springs consisting of blocks of india-rubber are indicated at A³, intermediate the driving member B³ and lugs C³, formed in a plate or disk C', which carries the pawl D². In order to transmit the power of the driving mechanism B³ in its reverse stroke, one spring only may be used, as indicated at A⁴, arranged between the driving member B³ and a lug C³ on the disk C'.

In Fig. 5 is shown another embodiment of our invention. In this construction B⁴ is the driving member, consisting of a rotatably-mounted ring, the bearings of which are not shown, said ring having internal ratchet-teeth b⁴ and an arm b⁵, provided with a pin b⁶, to which the prime mover may be connected. The ratchet-teeth b⁴ of the ring B⁴ are engaged by pawls D² D³, carried by arms C² C³, loosely mounted on an axle H, upon which are also mounted wheels whose hubs are indicated at I' I². These hubs are provided with flanges i' i², into openings in which enter the ends of torsional rods A⁴, whose other ends enter corresponding openings in the hubs c² c³ of the arms C² C³. The said torsional rods or spring-bars A⁴ are preferably

pivotedly connected to the hubs c² c³ and the flanges i' i², as by the pivot-pins shown at k, thus preventing undue flexure of the spring-bars A⁴, while at the same time permitting them to be subjected to torsion. Instead of a single oscillation there may also be employed for driving purposes two or more oscillations shifted in phase.

In the modification shown in Fig. 6 there are two separate arms C⁴ and C⁵, whose oscillations are shifted in phase relatively to each other by preferably one hundred and eighty degrees. Each of the two arms carries a pawl D⁴ D⁵, which pawls gear alternately in the ratchet-wheel E². The arms C⁴ and C⁵ are driven by the arms B⁵ and B⁶ through the springs A⁵ and A⁶, respectively, which are connected in any suitable manner with the arms C⁴ and C⁵, for instance, by the arms a⁵ and a⁶, as shown in Fig. 6. The arms B⁵ and B⁶ are oscillated in opposite directions by two crank-pins keyed on the shaft at one hundred and eighty degrees apart or by a suitable bell-crank or a rocking beam; but as the mass of the driven mechanism can be made sufficient, even in the case of a single driving mechanism, to fully equalize the power impulses this arrangement is not absolutely necessary in most cases.

The construction shown in Fig. 7 differs from that of Fig. 6 in that the resilient members A⁷ A⁸ are arranged to be operated by two driving members B⁷ B⁸, connected to a common reciprocating element L.

In Figs. 8 and 9 is shown a complete device embodying our invention, in this case an internal-combustion engine being shown as the prime mover. These views illustrate a suitable arrangement of the pawls for a high speed of operation and the means for controlling their operation and for reversing their direction of operation. In these views, M indicates an engine-cylinder, m the piston, and m' the piston-rod, connected to one end of an arm B⁹, whose other end extends through an opening in a tubular axle N and is fixed to a torsional rod A⁹, mounted in bearings n within the tubular shaft N, the latter in turn being carried by suitable supports—as, for example, the support indicated at O, Fig. 9. It is to be understood that the tubular axle and the torsional rod extend each way from the arm B⁹ and that at each end of the axle and rod is placed a wheel and transmitting mechanism; but in the drawings only one of such wheels and transmitting mechanisms is shown. Upon the ends of the tubular axle are mounted suitable wheels, one of which is shown at P, Fig. 9, the usual ball-bearings being provided between the axle and wheels, as indicated at n'. The outer face of the wheel is provided with a hub P', in which is mounted a ratchet-wheel E⁹, having internally-arranged ratchet-teeth, as indicated at q, Fig. 8, these teeth, however, not

being shaped like ordinary ratchet-teeth, but merely rounded, as will be clear from said Fig. 8. The hub P' is made in two parts, held together by bolts p' p², Figs. 8 and 9, one of said bolts holding the two ends of a band-brake R, which passes around the ratchet-wheel E⁹, being located within a circumferential groove in the outer periphery of said ratchet-wheel, as will be clear from Fig. 9. The band-brake serves as a friction device to lock or hold the ratchet-wheel to the hub P' of the wheel P, while in case of the wheel encountering an excessive resistance the band-brake will slip and allow the ratchet-wheel E⁹ to turn independently of the wheel. One end of the band-brake R is provided with a spring r, Fig. 8, in order to maintain a certain tension in the band-brake, and thereby compensate for wear and also in order that the band-brake will slip at a less resistance upon backward movement of the ratchet-wheel E⁹. To the end of the torsional rod B⁹ is fixed a sleeve c⁹, which is journaled in a sleeve p³, carried by the wheel, as is clear from Fig. 9. The sleeve c⁹ carries an arm C⁹, having two wings or lugs c¹⁰ c¹¹, the purpose of which will be described hereinafter. The arm C⁹ also carries a socket c¹², to which are connected the pawls D⁹ D¹⁰, serving to engage the teeth of the ratchet-wheel E⁹. The pawls are pivotally mounted in the socket c¹² and are connected with each other by elastic material, such as leather, rubber, or a steel spring c¹³. The free ends of the pawls project through and are fastened in spring-stirrups C¹⁴ by means of pins c¹⁵, Fig. 8. The two ends of each stirrup are provided with inward-projecting pins c¹⁶, which bear against the opposite sides of the ratchet-wheel E⁹, thus forming a frictional means which tends to draw the respective pawls D⁹ D¹⁰ into engagement with the ratchet-teeth. To each wing or lug c¹⁰ c¹¹ of the arm C⁹ is pivoted a pawl-adjusting lever S' S², one of which is shown in full lines in Fig. 9 and both of which are indicated in dotted lines in Fig. 8. These levers S' S² each have two projections s s', between which one end of the corresponding stirrup c¹⁴ is received. The opposite ends of the said levers S' S² are provided with pins s³ s⁴, which enter arc-shaped slots formed in a pawl-operating rod T, (shown in dotted lines in Fig. 8 and in cross-section in Fig. 9,) this rod T having a slot into which the end of the sleeve c⁹ projects, a cap t and a shoulder t' on the sleeve serving to prevent lateral play of the rod T. The end of the arm B⁹ and the piston-rod m' are connected by a pin m², and on this pin is also journaled a connecting-rod m³, engaging the wrist-pin m⁴ of a crank m⁵, fixed to a shaft m⁶, (shown in dotted lines in Fig. 8,) to which is attached a fly-wheel, (indicated in dotted lines at m⁷, Fig. 8.) The operation of this device is as follows: The engine being in operation the end of the arm B⁹ is reciprocated and

the crank m⁵ and its shaft and fly-wheel are set into rotation. The oscillation of the arm B⁹ tends to cause an oscillation of the arm C⁹, and hence of the pawls D⁹ D¹⁰ and the levers S' S². If the rod T be in the position indicated by the dotted lines in Fig. 8, the lever S² does not strike its spring-stirrup c¹⁴. Hence the pawl D⁹ will be free to engage the teeth of the ratchet-wheel during the upward motion of the arm C⁹, the friction of the corresponding spring-stirrup C¹⁴ against the faces of the ratchet-wheel serving to draw the said pawl C⁹ into positive engagement with the teeth of said ratchet-wheel, while on the backward or downward movement of the arm C⁹ the friction of the said spring-stirrup will tend to disengage the pawl C⁹ from the teeth of said ratchet-wheel. During this time the projection s' on the lever S' will keep the spring-stirrup of the pawl D¹⁰ in such a position that said pawl cannot engage the ratchet-teeth. Hence the oscillation of the arm B⁹ will tend to rotate the wheel in the direction of the arrow x, Fig. 8. If now the rod T be moved downward, the levers S' and S² will be swung on their pivots c¹⁰ c¹¹ and the pawl D⁹ will be thrown out of engagement, while the pawl D¹⁰ will be thrown into engagement, with the teeth of the ratchet-wheel, so that in this way the oscillations of the arm B⁹ will tend to drive the wheel in a direction opposite to that indicated by the arrow x, Fig. 8. When the rod T is intermediate its two extreme positions thus far described, the levers S' S² are in their intermediate positions and both pawls D⁹ D¹⁰ are out of engagement with the ratchet-teeth, and there will not be any movement of the ratchet-wheel. The elastic connection c¹³ between the two pawls serves to cushion the shock due to the inertia of the parts when oscillating rapidly. The frictional connection between the ratchet-wheel E⁹ and the wheel P through the band-brake R serves to prevent a fracture of the parts of the driving mechanism when a resistance is applied suddenly to the wheel or when the driving mechanism is set in operation suddenly. At the same time the friction of the band-brake is great enough to transmit the maximum power which is intended to be transmitted. It will be seen that the fly-wheel m⁷ and the other moving parts will have a certain amount of stored energy. If the wheel P encounters no resistance, there will be no distortion of the torsional spring bar or rod A⁹, Fig. 9. If, however, the wheel P is held firmly against rotation and if the friction of the brake-band R be so great that it will not allow the ratchet-wheel E⁹ to move, the engine will during its outward stroke exert its force in twisting the rod A⁹, Fig. 9, while on the inward stroke the potential energy of the said rod A⁹ is returned to the engine as kinetic energy, tending to drive the piston m inward more rapidly.

idly than it would otherwise go, and thus increasing the rotation of the crank m^5 and fly-wheel m^7 —that is to say, during the forward movement of the piston the energy of the engine is converted into potential energy in the spring-rod A^9 , and this potential energy is restored to the engine during its backward stroke. When the wheel P is free to move, but encounters some resistance, the spring-rod A^9 is first distorted through a certain angle of torsion until the reaction of the spring-rod is equal to the resistance of the wheel P , after which the power of the engine is transmitted directly to the wheel P , in which case a part of the energy of the engine is stored in the spring during the forward stroke and the remaining energy of the engine is expended in doing useful work in overcoming the resistance of the wheel, while on the return stroke of the engine the potential energy stored in the spring-rod is returned to the engine. Moreover, as the greater the resistance the greater the angle of distortion of the spring-rod A^9 , therefore the less the duration of time that the engine is transmitting useful work to the wheel P , and consequently the greater the speed the engine can acquire on the inward stroke. Thus the result is that the time of application of the real load to the engine is inversely proportional to the amount of such load. In this way it is possible for an engine to overcome a resistance which it could not overcome if such resistance were applied continuously. This is on the same principle which has often been employed in driving an automobile up a grade too steep for it to overcome in the normal manner. In such event it is common to unclutch the engine from the driving-wheels, run the engine until it has acquired a high speed, and then suddenly throw in the clutch, and thus use the energy of the moving parts to drive the vehicle up the grade, and so soon as this has slowed the engine down to a point when it is about ready to stop the clutch is released again and the process repeated. Our device operates on substantially this principle, but is automatic in the application and removal of the load and applies and removes the load at each revolution of the engine, so that a substantially constant number of revolutions per unit of time may be made by the engine, while the revolutions of the driven wheel may vary inversely according to the resistance encountered. In order that this result may be accomplished, it is important that the spring-rod or other resilient member be capable of storing the entire energy of the engine for one stroke, for if it could not then when it had stored a part of it either the engine would stop or the resilient member would break, if the resistance is not too great.

In Figs. 10 and 11 are shown arrangements of the resilient members A^{10} , which permit

the use of long spring-rods in a relatively short length, this being done by connecting the driving member B^{10} to a tube V , to whose opposite ends the rods A^{10} are connected, each rod extending the full length of the tube V and beyond the corresponding end of the same, the driven members being indicated at C^{10} .

The self-regulating driving-gear herein described and the combinations thereof are mainly adapted for application to vehicles; but they may also be employed in every other case where their characteristic feature, the self-regulation, is useful—such as, for example, in ships, elevating machinery, lifts and hoists, pumps, machine-tools, &c. Finally, it may be stated that the springs for transmitting the driving power may also be arranged longitudinally or diagonally of the vehicle, in which cases of course connecting elements or links should be provided for the purpose of transferring the oscillations (or the rotary motion produced by the oscillations) into the plane of the wheels.

Having thus fully described our invention, what we claim is—

1. The combination, with a driving mechanism having a rotating part capable of storing kinetic energy, of automatic mechanism for intermittently applying a load to said driving mechanism during a part of each rotation which part is an inverse function of the said load.

2. In a device of the class described, an oscillating part designed to be operated from a prime mover, a driven wheel, a moving part operated by said oscillating part, means for connecting said moving part with the driven wheel on movement in one direction and for disconnecting it on movement in the opposite direction, and a plurality of spring-rods connecting the oscillating member with said moving part, substantially as described.

3. In a device of the class described, an oscillating arm designed to be operated from a prime mover, a driven wheel, a moving part located in proximity to said driven wheel, means for causing said moving part to be put into engagement with said wheel on movement in one direction, and to be disengaged therefrom on movement in the opposite direction, and a torsion-spring connecting said oscillating arm and moving part, substantially as described.

4. The combination, with a vibratory driving element having a fixed stroke, of a vibratory driven element, a yielding connection between said driving and driven element, and means for converting the vibratory motion of the driven element into a unidirectional movement.

5. The combination, with a vibratory driving element, and a driven element, of a yielding connection between the driving and driven elements capable of storing substan-

tially the entire energy of the driving element for one stroke of the latter.

6. The combination, with a vibratory driving element having a fixed stroke, of a driven element, and a yielding connection between said driving and driven elements capable of storing substantially the entire energy of the driving element for one stroke of the latter.

In witness whereof we have hereunto set our hands in presence of two witnesses.
